UNITED STATES PATENT OFFICE.

ALFRED JOYCE, OF MONTREAL, QUEBEC, CANADA.

DESIGN FOR A MOLD FOR JELLY, &c.

SPECIFICATION forming part of Design No. 16,174, dated July 21, 1885.

Application filed June 8, 1885. Term of patent 7 years.

To all whom it may concern:

Be it known that I, ALFRED JOYCE, a subject of the Queen of Great Britain, residing at the city of Montreal, in the District of 5 Montreal and Province of Quebec, Canada, have invented and produced a new and original Design for Molds for Shaping Jellies, Ice-Creams, Jam-Cheese, and Similar Confectioneries and Cookeries, of which the following is 10 a specification, reference being had to the accompanying drawings, forming part thereof.

Figure 1 is a plan view of my newly-designed mold. Fig. 2 is a longitudinal vertical sectional elevation of the same on line 15 x x, Fig. 1. Fig. 3 is an end view of the mold.

The features of my design consist in a mold of oblong configuration in plan, as shown in Fig. 1, and curved transverse configuration,

as shown in Fig. 3, with parallel transverse 20 corrugations A.

The mold may be provided with a cover, B, or not, as desired; but neither the material out of which the mold is formed nor the said cover B, as shown, forms any part of the de- 25 sign.

I claim—

The design for a mold for jellies, &c., herein shown and described, the same consisting of a mold having an oblong or rectangular 30 configuration in plan, and a curved configuration in cross-section provided with transverse parallel corrugations.

A. JOYCE.
